tion of Delaware

Original application July 19, 1937, Serial No.
154,377. Divided and this application May 20,
1939, Serial No. 274,678

12 Claims. (Cl. 178—31)

This invention relates to printing telegraph systems and apparatus and more particularly to two channel systems of telegraphic transmission for controlling telegraphic recorders.

5 This application is a division of application Serial No. 154,337 filed July 19, 1937.

An object of the invention is the provision of a relatively simple telegraph system by utilizing two transmission channels for character selection and printing.

10 Another object of the invention resides in the provision of means for controlling transmission of impulses over two channels of transmission, comprising two groups of transmitting elements, 15 one group for each channel, and means whereby said elements are operative initially to impress character selecting impulses over each channel in staggered manner, secondly to impress printing impulses coincidentally over said 20 channels, and finally to impress restoration impulses in staggered manner over each channel.

In accordance with the present invention, signal impulses are transmitted over a two-channel or two-wire system to a printing apparatus 25 whereat one line wire is connected through one ratchet-controlling magnet to a winding of a printing magnet, and the other line wire is connected through a second ratchet-controlling magnet to the same winding of the printing 30 magnet. Since the printing magnet is marginal in operation, it responds only to current applied simultaneously on both line wires, and character printing is effected only when both windings of the ratchet-controlling magnets and the winding 35 of the printing magnet are energized. Each character signal consists of three parts; namely, a plurality of stepping impulses, a prolonged printing impulse, and a plurality of restoration impulses, all of which occur concurrently on 40 both line wires. For example, the stepping impulses occurring on one line wire control the stepping of a type wheel one thirty-sixth of a revolution per impulse, and the stepping impulses occurring on the second line wire control the 45 stepping of the type wheel one-sixth of a revolution per impulse. Although these positioning impulses exist on both line wires concurrently or exist during the same signal period but not simultaneously, the impulses on one line wire 50 are staggered with respect to the impulses on the other line, so as not to energize the print magnet prematurely. The maximum number of impulses on either line necessary to step the type wheel from its zero or starting position to 55 the last one of its thirty-six positions is five.

The second part of the character signal consists of a prolonged impulse occurring on both lines simultaneously and functions to operate the printing magnet which is designed to operate in response to greater current than the selecting or ratchet-controlling magnets, hence the requirement that the current on both lines simultaneously be necessary to operate the printing magnet. The third part of the signal consists of a series of impulses, occurring on both 10 line wires concurrently, six on each wire, and staggered similarly to the positioning impulses, so as to affect only the ratchet-controlling magnets and not the printing magnet, the function of which is to effect the restoration of the type 15 wheel to its initial or starting position. Thus, responsive to the restoration impulses is a restoration mechanism which prevents said impulses from rotating the type wheel further than to its 20 zero or starting position.

The above and other objects of the invention will be apparent from the following description when taken in conjunction with the accompanying drawings, wherein like reference characters 25 designate similar parts throughout the several views, and in which,

Fig. 11 is a schematic electrical circuit embodying the transmitter shown in Fig. 9. 50

Having reference to Figs. 1 to 4, the framework of the printing apparatus co-operable with the transmitting arrangement of the present invention comprises a base plate 11 supporting a mounting plate 12 attached thereto through 55

the instrumentality of a bar 13 by means of screws 14. A U-shaped bracket 15 is fixed to the mounting plate 12, and together with the mounting plate 12 provides a journal bearing for a type 5 wheel shaft 16, as seen in Fig. 3. Fixed to shaft 16, to the right of mounting plate 12, as viewed in Fig. 3, is a type wheel 17 which has associated therewith a star wheel 18. Between the web of bracket 15 and mounting plate 12, shaft 16 carries thereon a sleeve 19 and a pinion gear 21, the latter pinion being fixed to the shaft 16. Integral with sleeve 19 is a ratchet wheel 22 in which is journaled a shaft 23 which carries fixed thereon, planetary gears 24 and 25 disposed one on 10 each side of the ratchet wheel 22. The planetary gear 25 meshes with the pinion 21, and planetary gear 24 meshes with a pinion 26 which is integral with a sleeve 27 loosely mounted on the sleeve 19. A ratchet wheel 28 is also integral with the 15 sleeve 27. Fixed to shaft 16 to the left of mounting bracket 15 (as viewed in Fig. 3) is a collar 29 which carries a spring post 31 (as viewed in Fig. 2) to which is connected one end of a coiled spring 32, the other end of which is connected to 20 a pin 33 carried on a blocking segment 34 loosely mounted on shaft 16, the function of which will hereinafter appear.

As viewed in Fig. 2, ratchet wheel 22 has associated therewith a pawl 35 carried at the extremity of a pawl operating lever 36 which is associated with an armature 37 of an electromagnet 38. Electromagnet 38 is carried on a bracket 39 which in turn is mounted on a bracket 41 secured to the mounting plate 12. The armature 37 is pivotally supported at 42 to bracket 39 and is biased in a clockwise direction by a spring 43. Spring 43 thus normally, when magnet 38 is de-energized, maintains pawl operating lever 36 against stop portion 44 of a stop bracket 45. 30 Ratchet wheel 28 has associated therewith a pawl 46 carried at the extremity of a pawl operating lever 47 which is integral with the armature 48 of an electromagnet 49. Electromagnet 49 is carried on a bracket 51 which is supported 35 on a bracket 52 secured to mounting plate 12. Armature 48 is pivotally supported at 53 on bracket 51 and is biased in counterclockwise direction by a spring 54, which normally maintains pawl operating lever 47 against an adjustable 40 stop 60.

A printing magnet 55 is supported through angle brackets 56 and 57 to a plate 58 which in turn is carried by an angle bracket 59 secured to mounting plate 12. In the present embodiment, magnet 55 is provided with two windings, one of which controls an armature 61 pivotally mounted at 62 to the plate 58. Integral with armature 61 is a printing control lever 63 near the extremity of which is secured an extension 64 which acts on a plunger 65 carried in a bracket 66 secured to mounting plate 12. Plunger 65 co-operates with a laterally disposed flange 67 integral with a print hammer 68 (Fig. 1). Flange 67 is formed with a knife-edge to co-operate with 65 the star wheel 18, in well-known manner, to hold the type wheel in printing position during the printing operation. The print hammer 68 is biased to its downward position by a spring 69.

The printing magnet 55 is also provided with 70 a second winding which controls an armature 71 pivoted at 72 to plate 58. Armatures 61 and 71 are biased out of engagement with their pole faces by a common spring 73. Armature 71 is provided, integral therewith, with an extension 74 which is so conformed as to avoid the pawl

operating arm 47, and which terminates at its extremity in a hook portion 75 which co-operates with a plurality of pins 76 carried on the ratchet wheel 22.

Pawl operating lever 47 is provided with a vertically extending arm 77 which terminates at its upper extremity in a laterally directed portion 78. Portion 78 co-operates with the segment 34 during the performance of the restoration function as will presently appear.

In Fig. 4 is shown a diagrammatic representation of the type of signals transmitted by the transmitting apparatus according to the present invention and received over the two line wires for effecting the selective control and operation 15 of the printer shown in Figs. 1, 2, and 3. As previously indicated, each character signal consists of three parts; namely, the selecting or stepping impulses 83 and 84 comprising that portion indicated as 79, the prolonged printing im- 20 pulse comprising that portion indicated 81, and the restoration impulses 85 and 86 comprising that portion indicated 82. In Fig. 4 it may be noted that the selecting impulses 83 received over one line wire are staggered with respect to im- 25 pulses 84 received over the second line wire, it being understood that the number of impulses 83 or 84 vary with the character received. It will also be observed that the printing impulses 81 impressed on each line wire occur simultane- 30 ously and are prolonged in nature. Following the printing impulses are the restoration impulses 85 and 86 which are always, according to the present invention, six in number and are staggered as indicated. 35

Impulses 83 are impressed on electromagnet 38, and as each impulse is received, magnet 38 becomes energized and causes its armature 37 to rotate in a counterclockwise direction against the action of spring 43, thus rotating the pawl 40 operating lever 37 counterclockwise to raise pawl 35 to engage the next preceding tooth on the periphery of ratchet 22 preparatory to effecting rotation of said ratchet. Then upon de-energization of magnet 38 at the termination of 45 said impulse, armature 37 and lever 36 are actuated in a clockwise direction by the spring 43 so that pawl 35 rotates the ratchet 22 through one angular step. This movement of ratchet 22 causes the planetary gears 24 and 25 to be carried clockwise and since, during this movement the ratchet 28 is prevented from rotating, the gear 24 will be caused to rotate in a clockwise direction thus imparting the same movement to the companion planetary gear 25. This movement of planetary gear 25 causes pinion 21, and hence type wheel 17 and star wheel 18, to rotate in a counterclockwise direction as viewed in Fig. 2 (or a clockwise direction as viewed in Fig. 1). By properly proportioning the gears involved in 50 this gear chain, the type wheel 17 is moved one angular step representative of a single character space on the periphery of the type wheel for each actuation of pawl 35 by magnet 38.

When a character selecting impulse 84 is received over the second line wire, it causes the energization of magnet 49, which, upon energization, attracts its armature 48 to impart clockwise rotation to the pawl operating lever 47 against the action of its spring 54 sufficiently to 70 permit pawl 46 to engage the next preceding tooth on the ratchet wheel 28. Then, upon termination of said selecting impulse, magnet 49 becomes de-energized and spring 54 acts to rotate armature 48 and lever 47 counterclockwise, 75

thus actuating pawl 46 upwardly to effect the counterclockwise rotation of ratchet wheel 28 one angular step. Since ratchet wheel 22 is at this time held against rotation by its pawl 35, the 5 counterclockwise rotation of ratchet wheel 28 effects, through gear 26 and planetary gears 24 and 25 counterclockwise rotation of pinion 21 and type wheel 17, as viewed in Fig. 2. However, instead of rotating the type wheel only one angular 10 step representative of a single character space, type wheel 17 is rotated six angular steps or through the span of six character spaces of the periphery of the type wheel 17.

As previously mentioned character selecting 15 impulses are transmitted over both line wires concurrently except that the impulses on one wire are staggered with respect to the other, and the number of impulses transmitted over each line wire is determined by the character to be selected. Remembering that the type wheel is restored to an initial or starting position prior to the selection and printing of each character, it will be assumed that the fifth character on the type wheel counting from the initial or starting 20 position is to be selected. In this event, five impulses 83 will be transmitted over the first line wire (and none over the second line wire), thus energizing magnet 38 five times and rotating ratchet 22 through the angular distance of five 25 teeth to effect the rotation of the type wheel 17 correspondingly to present the fifth character on the type wheel (counting from the initial or starting position) to the printing point. Now, in the event that it is desired to print the eleventh 30 character on the type wheel counting from the initial or starting position, five impulses 83 will be transmitted over the first line wire to actuate magnet 38 and to rotate ratchet 22 five angular steps, and hence type wheel 17 five character 35 spaces; and one selecting impulse 84 will be transmitted over the second line wire to energize magnet 49 to operate lever 47 to effect the rotation of ratchet 28 one angular step, in a manner previously described, to cause the rotation 40 of type wheel 17, in a single movement, six character spaces which, when added to the five character space movement resulting from the operation of magnet 38, will have caused the type wheel to be moved through eleven character 45 spaces, thus presenting the eleventh character (counting from the starting position of the type wheel) to the printing point. It is thus seen that time has been saved in selecting the eleventh character on a type wheel by operating magnet 38 only five times and magnet 49 only once, instead of operating magnet 38 eleven times. Likewise, if magnet 49 is operated twice and magnet 38 is operated five times, the seventeenth character will be presented to the printing point. The 50 latter selection will have been achieved through the transmission of only seven impulses, instead of seventeen impulses, thus emphasizing the decided saving in line time. To select the thirty-fifth or last character on a type wheel (the 55 thirty-sixth or zero position being the blank position of the type wheel), only five impulses 83 need be transmitted to operate magnet 38 five times, and five impulses 84 need only be transmitted to operate the magnet 49 five times. Thus, 60 in all ten impulses have been transmitted instead of thirty-five.

After the transmission and receipt of the character selecting impulses 83 and 84, the selection of the character to be printed from the type 65 wheel has been determined, and following the

receipt of these selecting impulses 83 and 84 a prolonged printing impulse 83 is transmitted over both line wires simultaneously, thus energizing the print magnet 55, causing armature 61 thereof to be attracted and printing arm 63 5 to be actuated in a counterclockwise direction against the action of spring 73 to impart, through portion 64, upward movement to plunger 65, which through lateral portion 67 imparts counterclockwise movement (as viewed in Fig. 1) to 10 printing hammer 68, thus throwing the pallet portion of the printing arm 68 against the type wheel 17. At the same time the knife-edge of portion 67 co-operates with the star wheel 18 to prevent movement of the type wheel 17 during 15 the performance of the printing function.

The tape 87 is directed in tape guide 88 through the printing area. Engaging tape 87 through a slot (not shown) in the tape guide 88 is a tape spacing roller 89 which is provided, as is common practice, with a knurled periphery and which, to effect movement of the tape, co-operates with a pressure roller 91 carried on a lever 92 which is spring biased in a counterclockwise direction (as viewed in Fig. 1) by a 25 spring 93. Roller 89 is mounted on a shaft 94 (Fig. 2) to which is also fixed a spacing ratchet 95. Co-operating with spacing ratchet 95 is a pawl 96 which is carried at the extremity of the printing lever 63. Thus, upon each operation of 30 lever 63 in response to the printing impulse 81, the pawl 96 is reciprocated thereby engaging the next tooth on the ratchet 95 and upon a downward movement of pawl 96, ratchet 95 is rotated one angular step in a clockwise direction (as 35 viewed in Fig. 2) thus causing roller 89 to be rotated one angular step in a counterclockwise direction (as viewed in Fig. 1). A detent spring 97 is provided to prevent back spacing of the ratchet wheel 95 during the performance of the 40 spacing operation. Associated with the type wheel 17, as viewed in Fig. 1, is an inking roller 98 carried on a lever 99 biased by a spring 100.

As previously indicated, the third part of each 45 character signal comprises a plurality of impulses over each line wire, sufficient in number to insure the stepping of the type wheel forward (in the same direction as for character selection) to its starting or zero position. Since six impulses transmitted over each line wire is sufficient to rotate the type wheel a complete revolution, this number of impulses on each line has been chosen to effect restoration. Of course, the extent to which it is necessary to rotate the type wheel to its zero position after the selection of 50 a character varies with the character selected. Therefore, it is necessary to provide mechanism to prevent rotation of the type wheel farther than to its zero position. To achieve this result in connection with the six-step magnet 49, the segment 34 and arm 77 are provided, and in connection with the one-step magnet 38, the pins 76 55 and arm 74 are provided.

The magnets 38, 49, and 55 are connected in 60 the manner shown in Fig. 8 wherein the magnet 38 is included in one line wire 314 and the magnet 49 is included in the other line wire 315, magnet 55 being connected to both line wires so that impulses transmitted over line wire 314 will 65 pass through magnet 38 thence through magnet 55 to ground. In the form of the invention shown in Fig. 2, the magnet 55 is provided with two windings, one of which is marginal in character (and controls armature 61) so that the 70 impulses transmitted over only one of the line 75

wires will not energize the marginal winding of the magnet. On the other hand, it requires the total current on the two wires to effect the energization of said marginal winding of magnet 5. Magnet 55 is also provided with a second winding which responds to the selecting and restoration impulses over either wire to cause the operation of armature 71.

Now, when the restoration impulses 85 are transmitted over line wire 314, they will pass through magnet 38 and also the second mentioned winding of magnet 55. The effect of restoration impulses 85 on magnet 38 will be to operate arm 36 and pawl 35 to cause the clockwise rotation of ratchet wheel 22. However, since these restoration impulses also pass through the second mentioned winding of magnet 55, armature 71 is operated to rotate lever 74 clockwise to bring hook portion 75 into the path of pins 76. Thus, pawl 35 will continue to actuate ratchet wheel 22, in response to the restoration impulses 85, only until one of the pins 76 is intercepted by the hook portion 75 after which the remaining restoration impulses 85, if any, will have no effect. During the character selecting operation, the actuation of arm 74, and hence hook portion 75, in response to impulses 83 and 84, will have no arresting effect on the ratchet wheel 22, for the reason that the maximum distance that ratchet 22 may be rotated during a character selecting cycle is five steps, which is less than the number of steps between successive pins 76.

Similarly, the restoration impulses 86 transmitted over line wire 315 will pass through magnet 49 and said second winding of magnet 55. The effect of staggering impulses 85 and 86 is to maintain lever 74 steadily in its clockwise position, thus giving the effect of a continuous current on the second winding of magnet 55. The reception of the restoration impulses 86 by magnet 49 will cause lever 47 and pawl 46 to rotate ratchet wheel 28 step by step in a counterclockwise direction. As previously described, lever 47 is provided with a vertically extending arm 77 having a laterally extending portion 78. Thus, as lever 47 is oscillated, the portion 78 is reciprocated vertically. Portion 78 is thus free to reciprocate vertically until the segment 34 is presented in its path, whereupon oscillation of lever 47 is prevented. In this manner, type wheel 17, during the restoration operation, can be moved in six-step or six-character-space intervals until segment 34 is presented beneath the portion 78, after which the remaining restoration impulses, if any, will have no effect upon lever 47. The mechanism is so designed that when a pin 76 is intercepted by hook portion 75, and the portion 78 is intercepted simultaneously therewith by segment 34, the type wheel 17 will have reached its zero or starting position with the blank portion on the periphery of the type wheel presented to the printing point.

Segment 34, as previously described, is yieldably connected to shaft 16 by means of coil spring 32. The purpose of this is to prevent segment 34 during the character selection operation, from binding against the lateral portion 78; that is, assuming that segment 34 during character selection is presented with its forward edge 101 just to the right of the vertical path of portion 78, the lever 47 in response to a selecting impulse will be actuated in a clockwise manner, thus bringing portion 78 downwardly into the path of edge 101. Then on its upward move-

ment, lever 47 will actuate ratchet wheel 28 to cause its counterclockwise rotation. However, before ratchet wheel 28 has advanced very far, edge 101 will impinge against portion 78 which has not yet escaped the segment 34. Without the yieldable spring connection between segment 34 and shaft 16, the pressure of pawl 46 against ratchet wheel 28 by means of spring 54 would cause segment 34 to bind against portion 78, thus possibly injuring the mechanism. To compensate for this, segment 34 is permitted to yield and pawl 46 is permitted to complete its action upon ratchet wheel 28, whereafter when portion 78 clears the segment 34, segment 34 will be biased by spring 32 to its normal counterclockwise position.

Transmitting mechanism

In Figs. 5 to 11, inclusive, are shown various forms of transmitters and circuits therefor which may be employed in connection with the receiving printer shown in Figs. 1 to 3. In Figs. 5 to 7, inclusive, is illustrated a keyboard transmitter of the type shown and disclosed in United States Patent No. 1,595,472. As shown in Figs. 5 and 6 the keyboard portion, indicated generally as 301, is provided with a set of keys 302 arranged similarly to the well-known typewriter keyboard, and, as illustrated in Fig. 5, key levers 303 associated with the keys 302 are pivotally mounted on a common shaft 304 and are spring held in normal horizontal position by individual springs (not shown). Arranged transversely below the key levers 303 (Fig. 6), in operative relation thereto, are a series of V-notched selector bars 305 which are adapted to be operated permutably, in well-known manner, in accordance with the key depressed.

The selector bars 305 are pivotally articulated to a corresponding series of locking latches 306 which are adapted to be rocked to either of two positions thereby. Associated with latches 306 is a corresponding series of contact levers 307 for making and breaking contacts 308. Contact levers 307 co-operate with individual contact cams 309 mounted on shaft 311. The shaft 311 is provided with a single revolution clutch mechanism (not shown) which is controlled by a universal bar member as set forth in Patent No. 1,595,472.

The operation of the transmitting unit consists essentially in the depression of a key lever 303 which effects the arrangement of the set of selector bars 305 periodically in accordance with a predetermined code combination, the setting of which determines the position of the locking latches 306. The rotation of the cams 309 is initiated substantially simultaneously with the setting of the locking latches 306, and a locking loop 312 controlled by a cam 313 is permitted to rotate in a counterclockwise direction (Fig. 6) to effect the locking of latches 306. The setting of the locking latches 306 determines whether the contact levers 307 shall or shall not be affected by their associated cams 309 to cause the opening or closing of their associated contacts 308 to transmit over a signal line (as will appear presently from a description of Fig. 8) to the receiving station a predetermined combination of signaling impulses. The respective notches in the cams 309 are arranged in a spiral progression so that upon the rotation of the cam assembly, the contacts 308 will be controlled successively.

In the present form of transmitter, the con-

tact cams 309 are eight in number and are divided in groups of four each, each group of four being connected to a separate line wire over a two-wire telegraph system. In Fig. 7 is shown 5 the series of eight contact cams 309 with their respective contact levers and contacts. In this illustration, contact cams 321, 322, 323, and 324 comprise one group, the contacts 308 of which are connected over line wire 314 of Fig. 8, and 10 contact cams 331, 332, 333, and 334 comprise a second group, the contacts 308 of which are connected over a second line wire 315 of Fig. 8. It will be noted that contact cams 321 and 331 are provided with a single depression in response 15 to which a single impulse is transmitted through a contact 308 for each revolution of the cam. It will be noted further that cams 322 and 323 and cams 332 and 333 are each provided with two adjacent notches so that for each revolution of 20 these cams, two impulses will be transmitted. Then to enable the sending of one to five character impulses over each wire 314 and 315, the cams in each group may be selected in proper combinations; for example, to send a single impulse 25 over line 314, cam 321 only would be operated. To transmit two impulses over line 314, cam 322 or cam 323 will be operated. To send three impulses over line 314, cam 321 would be operated simultaneously with cam 322 or 323. To 30 send four impulses over line 314, cams 322 and 323 would be operated simultaneously, and to transmit five signals over the line all of the cams 321, 322, and 323 would be operated simultaneously. The same permutable operation of the 35 second group of cams 331, 332, and 333 is effected to transmit signals over line 315. It will be observed that the notches of each group of cams are arranged in a progressive manner.

Cams 324 and 334 are not controlled by lock 40 latches 306 and are permitted to rotate invariably for every operation of transmitting shaft 311. Each of the cams 324 and 334 is so cut as to transmit (following the character selecting impulses) first the prolonged printing 45 impulse and thereafter six restoration impulses.

Having reference to Fig. 8 there is shown a 50 circuit diagram for a two-wire telegraph system employing the transmitter shown in Figs. 5 to 7 and printers according to Figs. 1 to 3; for example, herein described. According to this 55 system, impulses in accordance with the diagram shown in Fig. 4 are transmitted from battery 335, through contacts 308, over line wires 314 and 315, through their respective stepping magnets 38 and 49, thence through printing magnet 55 to ground.

In Figs. 9 to 11 is shown a dial type of transmitter. In accordance with this form of transmitter, a series of dialing keys 351 are disposed 60 above a casing 352, and integral with each dialing key is a key lever 353 loosely carried upon a shaft 354. Each of the key levers 353 is provided with oppositely directed arcuately shaped arms 355 and 356, the upper arcuate edges of 65 which are notched in code manner. Associated with the arm 355 of each of the key levers 353 is a pin 357 carried on a common rod 358 suitably journaled in the casing 352. There is also 70 carried on the rod 358 a contact operating pin 359 which co-operates with the upper blade 361 of contact 362. The assembly comprising rod 358 and pins 357 and 359 are biased in their clockwise direction (as viewed in Fig. 9) by a spring 363. When a key lever 353 is rotated in a counter-clockwise direction, the code projections on

the arm 355 rock the rod 358 repeatedly in a clockwise direction and rotate arm 359 away from the contact 361. Then, upon the return of key lever 353 to its rightward or clockwise position (as shown in Fig. 9), the code projections 5 on arm 355 will again rock rod 358 repeatedly in a counter-clockwise direction against the action of spring 363 to close the contact 362 intermittently to transmit impulses over the line wire, 10 as will be hereinafter explained.

Similarly there is associated with the arm 356 of each of the key levers 353 a pin 364 which is carried upon a common rod 365. There is also fixed to rod 365 a contact operating pin 366 which operates a contact 367. As a key lever is rotated 15 counter-clockwise, the code projections upon arm 356 act, through pins 364, to rock rod 365 repeatedly in a clockwise direction and rotate arm 366 away from contact 367. Then, upon return of the key lever 363 to its clockwise position, the 20 code notches on arm 356 act to rock rod 365 repeatedly in a counter-clockwise direction against the action of its spring 368 to close contact 367 intermittently to transmit signal impulses over 25 a second line wire.

According to the presently described form of the invention, means is provided for preventing the operation of more than one key lever 353 at a time; that is, when one key lever 353 is operated, all of the remaining key levers are locked against 30 operation. To achieve this result, an arm 369 is associated with each key lever which arms 369 are fixed to the shaft 354. Pivotally carried on key lever 353 adjacent the outer extremity of arm 369 is a bell crank lever 371. There is also 35 carried on key lever 363 a bell crank lever 372, and bell cranks 371 and 372 are biased attrahently by a common spring 373. Extending longitudinally through the casing 352 and supported therein is a rod 374 which cooperates with bell 40 cranks 371 and 372. Also fixed to the shaft 354 is an arm 375 to the extremity of which is connected one end of a spring 376, the other of which is anchored to the casing 352. Thus, in this manner, all of the arms 369 are biased to their clockwise position against a stop 377 carried on each of the key levers 353.

When the arms 369 assume their clockwise position against stops 377, their ends 378 thereof also bear against bell cranks 372 to rotate the latter sufficiently to remain disengaged from bar 374 as indicated in Fig. 9. Also, when key lever 363 is held in its clockwise position, bell crank lever 371 bears against bar 374 in such a manner as to maintain its horizontal arm disengaged from end 378 of arm 369.

Now, when a key lever 353 is operated by means of its associated dialing key 351, and is thereupon actuated in a counter-clockwise direction, its pin 357 engages arm 369 and carries said arm 60 forwardly therewith. This action is rendered possible because arm 369 is still bearing against bell crank 372 to hold said bell crank disengaged from bar 374, and as lever 353 is moved counter-clockwise, bell crank 372 passes under the bar 65 374. Since all of the arms 369 are fixed to shaft 354, the remaining arms 369 will be moved independently of their associated key levers 353. Then, because of this operation of arm 369 independently of key levers 353, bell cranks 372 of 70 all but the operated key lever 353 will be free to be actuated by their respective springs 373, so as to bring the horizontal arms of bell cranks 372 into latching engagement with bar 374. Therefore, so long as arms 369 of all but the operated 75

key lever 353 remain out of contact with their respective bell cranks 312, all of the remaining key levers 353 are locked against operation. In Fig. 10 is shown a plan view of the dial transmitter with a part broken away to show the contact 362.

In Fig. 11 is shown a circuit diagram of a two wire telegraph system employing the dial transmitter shown in Figs. 9 and 10. In this system 10 the contact 362 is operated intermittently in accordance with the code notches on the arm 355 of a key lever 353 to transmit impulses over the first line wire 379 through a stepping magnet 381 and print magnet 382 to ground. Similarly, contact 367 is operated intermittently in response to the code notches on the arm 356 of a key lever 353 to transmit over a second line wire 383 signal impulses to a stepping magnet 384 thence through the print magnet 382 to ground. Since print 20 magnet 382 is of marginal operation, it will not respond to impulses received over either line wire singly but only when a printing impulse is received over both line wires 379 and 383 simultaneously. It is understood that the code notches 25 on arms 355 and 356 may comprise the character signaling impulses, the printing impulse, and restoration impulses in accordance with the signal indicated in Fig. 4.

Although the present invention has been disclosed in connection with certain specific embodiments thereof, it is understood that such embodiments are merely illustrative and not restrictive, and that all forms coming within the scope of equivalency of the appended claims are 35 intended to be covered by the invention.

What is claimed is:

1. In a telegraph transmitter, means for controlling transmission of impulses over two channels of transmission, comprising two groups of 40 transmitting elements, one group for each channel, and means whereby said elements are operative initially to impress character selecting impulses over each channel in staggered manner, secondly to impress printing impulses coincidentally over said channels, and finally to impress 45 restoration impulses in staggered manner over each channel.

2. In a dial transmitter for transmitting signals over two transmission channels, a plurality of 50 dialing keys, a pair of coded arms carried on each key, a pair of contacts, one included in each channel, and contact controlling means for each contact co-operatively associated with corresponding arms of said pairs of arms.

3. In a dial transmitter for transmitting signals over two transmission channels, a plurality of 55 dialing keys, a pair of coded arms carried on each key, a pair of contacts, one included in each channel, contact controlling means for each contact co-operatively associated with corresponding arms of said pairs of arms, and means controlled by each key for locking, during each actuation thereof, the remaining keys against operation.

4. In a dial transmitter for transmitting signals over two transmission channels, a plurality of 60 dialing keys, a pair of coded arms carried on each key, a pair of contacts, one included in each channel, and contact controlling means for each contact co-operatively associated with corresponding arms of said pairs of arms and effective to transmit over said channels concurrently 65 signals in accordance with the codes on said arms.

5. In a dial transmitter for transmitting sig-

nals over two transmission channels, a plurality of dialing keys carried loosely on a common shaft, a pair of coded projections carried on each key, a pair of contacts, one included in each channel, contact controlling means for each contact co-operatively associated with corresponding projections of said pair of projections, an arm associated with each dialing key and fixed to said common shaft, locking means carried by each key and controlled by said arms, and means effective upon each actuation of a key whereby the arm associated with the actuated key is interlocked therewith to actuate thereby all said arms simultaneously to render the locking means of the remaining keys effective to lock said remaining keys against operation.

6. In an apparatus for transmitting signals over two transmission channels, a series of contacts, a permutation code selector mechanism, two groups of contact controlling mechanisms, one group for each channel, and means whereby said mechanisms are controlled permutably by said selector mechanism and are operative in a single cycle to impress concurrently signal impulses over each channel in staggered manner, 25 followed invariably by a printing impulse occurring coincidentally on each channel and a definite series of restoration impulses occurring on each channel in staggered manner.

7. In a keying device, a shaft, a plurality of 30 keys carried loosely on said shaft, an arm associated with each key and fixed to said shaft, locking means carried by each key and controlled by said arms, and means effective upon each actuation of a key whereby the arm associated with the actuated key is interlocked therewith to actuate thereby all said arms simultaneously, to render the locking means of the remaining keys effective to lock said remaining keys against 35 operation.

8. In a keying device, a shaft, a plurality of 40 keys carried loosely on said shaft, an arm associated with each key and fixed to said shaft, a lock bar, dual bell crank locking means carried by each key and co-operable with said lock bar 45 and controlled by said arms, and means effective upon each actuation of a key whereby the arm associated with the actuated key is interlocked therewith to insure control of said shaft by said key lever and simultaneously to render the locking means of the remaining keys effective to lock said remaining keys against operation.

9. In a keying device, a shaft, a plurality of 50 keys carried loosely on said shaft, an arm associated with each key and fixed to said shaft, a lock bar, dual bell crank locking means carried by each key and co-operable with said lock bar and controlled by said arms, and means effective upon each actuation of a key whereby the arm associated with the actuated key is interlocked 60 therewith through the instrumentality of one of said bell cranks to insure control of said shaft by said key lever and simultaneously to render the locking means of the remaining keys effective, through the other of said bell cranks, to lock said 65 remaining keys against operation.

10. In a dial transmitter for transmitting signals over two channels, a shaft, a plurality of 70 dialing keys loosely mounted on said shaft, a pair of coded arms on each key, an arm associated with each key and fixed to said shaft, a pair of contacts, one included in each channel, contact controlling means for each contact co-operatively associated with corresponding arms of 75 said pairs of arms, locking means carried by

each key and controlled by said arms, and means effective upon each actuation of a key whereby the arm associated with the actuated key is interlocked therewith to actuate thereby all said 5 arms simultaneously to render the locking means of the remaining keys effective to lock said remaining keys against operation.

11. In a dial transmitter for transmitting signals over two channels, a shaft, a plurality of 10 dialing keys loosely mounted on said shaft, a pair of coded arms on each key, an arm associated with each key and fixed to said shaft, a pair of contacts, one included in each channel, contact controlling means for each contact cooperatively associated with corresponding arms of 15 said pairs of arms, a lock bar, dual bell crank locking means carried by each key and cooperable with said lock bar and controlled by said arms, and means effective upon each actuation 20 of a key whereby the arm associated with the actuated key is interlocked therewith to insure control of said shaft by said key lever and simultaneously to render the locking means of the re-

maining keys effective to lock said remaining keys against operation.

12. In a dial transmitter for transmitting signals over two channels, a shaft, a plurality of 5 dialing keys loosely mounted on said shaft, a pair of coded arms on each key, an arm associated with each key and fixed to said shaft, a pair of contacts, one included in each channel, contact controlling means for each contact cooperatively associated with corresponding arms of 10 said pairs of arms, a lock bar, dual bell crank locking means carried by each key and cooperable with said lock bar and controlled by said arms, and means effective upon each actuation of a key whereby the arm associated with the 15 actuated key is interlocked therewith through the instrumentality of one of said bell cranks to insure control of said shaft by said key lever and simultaneously to render the locking means of the remaining keys effective, through the other 20 of said bell cranks, to lock said remaining keys against operation.

HOWARD L. KRUM.
